UNITED STATES PATENT OFFICE.

ALFRED M. ZIEGLER, OF BOSTON, MASSACHUSETTS.

DESIGN FOR A SLIDE-BUCKLE.

SPECIFICATION forming part of Design No. 34,962, dated August 20, 1901.

Application filed July 17, 1901. Serial No. 68,704. Term of patent 14 years.

To all whom it may concern:

Be it known that I, ALFRED M. ZIEGLER, a citizen of the United States, and a resident of Boston, county of Suffolk, State of Massachusetts, have invented and produced a new and original Design for a Slide-Buckle, of which the following is a specification, reference being had to the accompanying drawing, forming part thereof.

10 The drawing in plan view shows a slide-buckle embodying my new design.

As shown in the drawing, the leading or material feature of my design consists of a slotted body A, presenting at its opposite 15 sides curved ears B, forming part of a com-

plete circle C, having lines c, presenting the appearance of a cord.

Having described my invention, what I claim as new, and desire to secure by Letters Patent, is—

20 The design for a slide-buckle as herein shown and described.

In testimony whereof I have signed my name to this specification in the presence of two subscribing witnesses.

ALFRED M. ZIEGLER.
